CLOCK RADIO OR SIMILAR ARTICLE

Keith D. Kitts, Glenview, Ill., assignor to Admiral Corporation, Chicago, Ill., a corporation of Delaware

Filed Oct. 13, 1965, Ser. No. 37,454

Term of patent 7 years

(Cl. D56—4)

Fig. 1.

Fig. 2.

Fig. 3.

FIG. 1 is a front elevational view of a clock radio or similar article, showing my new design;

FIG. 2 is a right side elevational view to a reduced scale, the opposite side being substantially a mirror image thereof; and

FIG. 3 is a front, top and right side perspective view thereof, to a reduced scale.

The dominant features of my new design are shown in solid lines in the drawing. Portions of the drawing figures are diagonally lined to indicate transparency, while the bottom of the front panel is lined to indicate contrast in appearance.

I claim:

The ornamental design for a clock radio or similar article, as shown and described.
